DESIGN FOR A COMBINED MIRROR AND SUPPORT

George C. Lynch, Los Angeles, Calif.

Application March 15, 1941, Serial No. 99,625

Term of patent 14 years

To all whom it may concern:

Be it known that I, George C. Lynch, a citizen of the United States, residing at 741 North Formosa Avenue, Los Angeles, in the county of Los Angeles and State of California, have invented a new, original, and ornamental Design for a Combined Mirror and Support, of which the following is a specification, reference being had to the accompanying drawing, forming part hereof.

Referring to the drawing:

Figure 1 is a perspective view of a combined mirror and support in a position when in use, showing my new design; and

I claim:

The ornamental design for a combined mirror and support, as shown.

GEORGE C. LYNCH.
